SLIPPER

Gustav Cohn, New York, N. Y.

Application October 20, 1951, Serial No. 17,054

Term of patent 7 years

(Cl. D7—7)

To all whom it may concern:

Be it known that I, Gustav Cohn, a citizen of the United States, residing at 350 Fifth Avenue, New York, New York, have invented a new, original, and ornamental Design for a Slipper, of which the following is a specification, reference being had to the accompanying drawing, forming part thereof, in which

Fig. 1 is a top plan view of a slipper showing my new design, and

Fig. 2 is a side elevational view thereof.

I claim:

The ornamental design for a slipper, substantially as shown.

GUSTAV COHN.
